Primary Examiner — John Windmuller*Assistant Examiner* — Steven Czyz(74) *Attorney, Agent, or Firm* — Aka Chan LLP(57) **CLAIM**

The ornamental design for an umbrella with solar panels, as shown and described.

DESCRIPTION

FIG. 1 shows a perspective view of a first embodiment of a design for an umbrella with solar panels.

FIG. 2 shows a top view of FIG. 1.

FIG. 3 shows a first side view of FIG. 1.

FIG. 4 shows a second side view of FIG. 1.

FIG. 5 shows a perspective view of a second embodiment of a design for an umbrella with solar panels.

FIG. 6 shows a top view of FIG. 5.

FIG. 7 shows a first side view of FIG. 5; and,

FIG. 8 shows a second side view of FIG. 5.

The broken lines in the figures depict portions of the umbrella with solar panels that form no part of the claimed design. The gray shading in the figures is surface shading that indicates claimed portions of the solar panels.
